(57) CLAIM

The ornamental design for a shoe, as shown and described.

DESCRIPTION

FIG. 1 is a bottom front perspective view of a shoe showing my new design;

FIG. 2 is a bottom view thereof;

FIG. 3 is a bottom rear perspective view thereof;

FIG. 4 is a front view thereof;

FIG. 5 is a front perspective view thereof;

FIG. 6 is a bottom front perspective view of a shoe showing an alternative embodiment of my new design;

FIG. 7 is a bottom view thereof;

FIG. 8 is a bottom rear perspective view thereof;

FIG. 9 is a front view thereof; and,

FIG. 10 is a front perspective view thereof.

The broken line treads within the shaded area in FIGS. 6-10 form no part of the claimed design. The unshaded broken line region within the shaded area in FIGS. 1-10 forms no part of the claimed design. The broken lines depicting the remainder of the shoe form no part of the claimed design.

1 Claim, 10 Drawing Sheets# US D934,546 S
